(57) **CLAIM**

The ornamental design for a grip for television camera lens, as shown and described.

DESCRIPTION

FIG. 1 is a top, front and left side perspective view of a grip for television camera lens showing my new design;

FIG. 2 is a front elevational view thereof;

FIG. 3 is a bottom plan view thereof;

FIG. 4 is a left side elevational view thereof; and,

FIG. 5 is a top, front and right side perspective view showing the present article attached to the television camera lens.

The portions of the grip for television camera lens in broken lines are shown for illustrative purposes only and form no part of the claimed design.

1 Claim, 5 Drawing Sheets
